Patented Oct. 15, 1918.

FIG. 1.

FIG. 3.

FIG. 2.

Inventor

Frederick A. Stahl,

By his Attorneys

Edgar, Tate & Co.

UNITED STATES PATENT OFFICE.

FREDERICK A. STAHL, OF NEW YORK, N. Y.

TOY.

1,281,866.

Specification of Letters Patent. Patented Oct. 15, 1918.

Application filed March 23, 1918. Serial No. 224,161.

To all whom it may concern:

Be it known that I, FREDERICK A. STAHL, a citizen of the United States, and residing at New York, in the county of New York and State of New York, have invented certain new and useful Improvements in Toys, of which the following is a specification, such as will enable those skilled in the art to which it appertains to make and use the same.

This invention relates particularly to what are known as souvenir toys, and the object thereof is to provide a device of this class which is designed to illustrate or demonstrate the expression "Over the top;" a further object being to provide a mechanical souvenir toy which will amuse and interest both young and old; and with these and other objects in view the invention consists of a device of the class specified, constructed and operating as hereinafter described and claimed.

The invention is fully disclosed in the following specification, of which the accompanying drawing forms a part, in which the separate parts of my improvement are designated by suitable reference characters in each of the views, and in which:

Figure 1 is a side view of my improved souvenir toy and showing the parts in their normal position;

Fig. 2 a central vertical sectional view of the device as shown in Fig. 1 and indicating the parts in a different position in dotted lines; and,

Fig. 3 a view similar to Fig. 2 but showing only a portion of the parts and showing the same in full lines in the position indicated in Fig. 2 in dotted lines.

In the practice of my invention I provide a top-shaped body *a* which is made in the form of an ordinary top, and which may be composed of any suitable material, and the body *a* is provided with a central cylindrical chamber *a*² which opens through the top of said body and extends downwardly thereinto about two-thirds of the vertical dimensions thereof and terminate in a flat bottom *a*³ below which is a tapered bore *a*⁴ which opens through the tapered end *a*⁵ of the body *a*, and around the top of the chamber *a*² is a collar or rim *a*⁶ provided in its inner walls with an annular groove *a*⁷ into which is sprung an open spring ring *b* which forms an inwardly

directed annular shoulder for the purpose hereinafter described.

Within the chamber *a*² is placed a spiral spring *c* which is adapted to bear on the bottom *a*³ of said chamber, and placed in said chamber is a vertically movable figure *d* mounted on a circular base or pedestal *d*² having a downwardly directed and tapered pin *d*³ adapted to fit in the tapered bore *a*⁴ and to project slightly below the bottom of the body *a* as shown at *d*⁴ when said figure is in its lowest position.

The figure *d*, in the form of construction shown, is designed to represent a soldier and is provided with the representation of a hat *d*⁵ which is really a part of said figure and which is adapted to rest on the flange or rim *a*⁶ of the body *a* when said figure is in its lowest position, and the figure *d* is also provided in the construction shown with a gun *d*⁶.

In assembling these parts the spring *c* is first inserted into the chamber *a*², after which the open ring *b* is passed up over the bottom part of the figure *d*, after which said figure is inserted into said chamber with the base or pedestal *d*² thereof resting on the spring *c*, after which the open spring ring *b* is passed into or secured in the groove in the collar or rim *a*⁶ of the body *a*, and this ring *b* is designed to hold the figure *d* in the chamber *a*² and prevent its removal therefrom.

When the figure *d* is depressed within the chamber *a*² as shown in Figs. 1 and 2, the spring *c* is compressed and the pin *d*³ is forced downwardly into the bore *a*⁴ so that it will be held therein by friction and against the operation of the spring *c*, and the appearance of the device at this time will be that shown in Fig. 1, and if pressure be applied to the bottom *d*⁴ of the pin *d*³, said pin will be loosened and the spring *c* will force the figure *d* up into the position shown in dotted lines in Fig. 2, in which the figure *d* will be projected above the top of the body *a*, and this upward movement of said figure is limited by the base or pedestal *d*² thereof striking the ring *b*, as clearly shown in Fig. 3, and said figure may be returned to the position shown in full lines in Fig. 2 by pressing on the top thereof and forcing it downwardly into the chamber *a*² and forcing the pin *d*³ into the bore *a*⁴ so that said figure

will be held in its depressed position by friction between said pin d^3 and the walls of the bore a^4 in the bottom of the body a .

My invention is not limited to the shape

5 of the body a nor to any particular design of the figure d , and said figure may be so made as to illustrate or represent any object, article, device or person, and various other changes in and modifications of the 10 separate parts of the construction herein described may be made, within the scope of the appended claims, without departing from the spirit of my invention or sacrificing its advantages.

15 Having fully described my invention, what I claim as new and desire to secure by Letters Patent, is:

1. A toy of the class described, comprising a body having a central vertical chamber 20 which opens upwardly and a tapered bore communicating therewith and opening downwardly through said body, a tensional device mounted in said chamber and adapted to bear on the bottom thereof, and a figure 25 mounted in said chamber and adapted to bear on said tensional device and provided with a tapered pin adapted to pass downwardly through said bore and to frictionally engage the walls thereof, said figure being 30 vertically movable in said chamber and adapted to be projected above the top of the body.

2. A toy of the class described, comprising a body having a central vertical chamber 35 which opens upwardly and a tapered bore communicating therewith and opening downwardly through said body, a tensional device mounted in said chamber and adapted to bear on the bottom thereof, and a figure 40 mounted in said chamber and adapted to bear on said tensional device and provided with a tapered pin adapted to pass downwardly through said bore and to frictionally engage the walls thereof, said figure being 45 vertically movable in said chamber and adapted to be projected above the top of the body, and means for limiting the upward movement of said figure in said chamber.

3. A toy device of the class described, comprising a body having a central vertical chamber which opens upwardly and a tapered bore which extends from the bottom of said chamber downwardly through said body, a spring mounted in said chamber and adapted to bear on the bottom thereof, and a figure inserted into said chamber and provided with a tapered pin adapted to pass downwardly through said bore and to frictionally engage the walls thereof.

4. A toy of the class described, comprising a body having a vertical cylindrical chamber therein which opens upwardly and at the bottom of which is a tapered bore which extends downwardly and opens through the 65 bottom of said body, and a vertically mov-

able figure placed in said chamber and having a tapered pin adapted to be forced downwardly through said bore and to frictionally engage the walls thereof.

5. A toy of the class described, comprising 70 a body having a vertical cylindrical chamber therein which opens upwardly and at the bottom of which is a bore which extends downwardly and opens through the bottom of said body, a vertically movable figure 75 placed in said chamber and having a pin adapted to be forced downwardly through said bore and to frictionally engage the walls thereof, a spring for forcing said figure upwardly, and means for limiting 80 said upward movement.

6. A toy device of the class described, comprising a top-shaped body having a central vertical chamber which opens upwardly and at the bottom of which is a bore which extends downwardly from said chamber and opens outwardly through the bottom of said body, and a vertically movable figure mounted in said chamber and provided with a pin adapted to be passed downwardly through 90 said bore and to frictionally engage the walls thereof.

7. A toy of the class described, comprising a top-shaped body in which is a central chamber which opens upwardly through said body and at the bottom of which is a bore which opens downwardly through said body, a vertically movable figure mounted in said chamber and provided with a pin adapted to be forced downwardly through said bore and to frictionally engage the walls thereof, means for forcing said figure upwardly, and means for limiting the upward movement thereof.

8. A toy device of the class described, comprising 105 a body portion having a vertically movable spring supported figure mounted therein and provided with a part which extends downwardly through said body portion and projects below the same when said figure is in its lowest position, and means for limiting the upward movement of said figure.

9. A toy device of the class described, comprising 115 a body portion having a vertically movable spring supported figure mounted therein and provided with a part which extends downwardly through said body portion and projects below the same when said figure is in its lowest position, and means for limiting the upward movement of said figure, said figure being normally held in its lowest position by frictional engagement with the body portion.

10. A toy device of the class described, 125 comprising a body portion having a vertically movable spring supported figure mounted therein and provided with a part which extends downwardly through said body portion and projects below the same.

when said figure is in its lowest position, means whereby said figure is held in its lowest position by frictional engagement with the body portion, and means whereby the 5 upward movement of said figure is limited.

In testimony that I claim the foregoing as my invention I have signed my name, in

presence of the subscribing witnesses, this 21st day of March, 1918.

FREDERICK A. STAHL.
